1 Claim. (Cl. 124—49)

The present invention relates to toy guns capable of discharging balls, wherein a plurality of magazines are provided within the body by turning to account the internal space thereof, and the magazine equipment has a common communicating passage which is either openable or at all times open for feed of balls, rendering it possible for the body to have within the largest possible magazine capacity, and for the random collections of many balls to travel in orderly manner from the auxiliary to the main magazine, thereby avoiding the trouble of picking up from without, for example by hand fingers, individual balls from the auxiliary to the main magazine for next discharge and securing the best feed of balls further down to the discharge bore.

In accordance with the invention, the provision specifically with the main and auxiliary magazines within the body, the main magazine lying either in the vicinity of or directly communicating with the feed portion, for example, in the form of feed hole, for guiding balls into the discharge bore, and the auxiliary magazine lying either disconnected from or not directly communicating with said feed portion, structurally renders it possible to make the most expedient use of the internal space of the body and effectively secure the largest possible capacity for the magazine equipment. The communication of the plurality of magazines with a common passage, either openable or open at all times, renders it possible for the individual balls in each of the magazines to travel in an orderly manner from the auxiliary to the main magazine and further down into the feed portion (hole): an advantage that the random collections of large number balls stored in a spacious magazine equipment automatically travel in line with the definite contemplation.

Accordingly, it is an object of the invention to provide toy guns capable of discharging balls, wherein there are provided at least two magazines as the main and auxiliary ones separately within the body by turning to account the internal space thereof, the plurality of magazines having a common communicating passage that allows balls to travel from an auxiliary magazine to a main magazine within the body.

It is another object of the invention to provide toy guns capable of discharging balls, wherein there are provided a plurality of magazines within the body by turning to account the internal space thereof and the communicating passage open at all times and common to said magazines so that shocks, vibrations or changes in position given to the body during discharge action or operation for discharge assist the balls to travel through the communicating passage from magazine to magazine.

It is another object of the invention to provide toy guns capable of discharging balls, wherein there are provided a plurality of magazines within the body by turning to account the internal space thereof and the communicating passage common to said magazines and furnished with the common shutter so that shocks, vibrations or changes in position given to the body during discharge action or operation for discharge assist the balls to travel through the shutter from magazine to magazine.

It is still another object of the invention to provide toy guns capable of discharging balls, wherein there are provided a plurality of magazines within the body by turning to account the internal space thereof, and, in obtaining

2

the largest possible capacity for the magazine equipment, the partition wall for this specifically selected to lie adjacent to the communicating passage, is freely designed in shape and angular inclination so, that undisturbed travel and feed of balls down into the feed hole is secured.

A preferred embodiment of the invention will be set forth in the following description with references being made to the drawing, which is a longitudinal sectional view of a toy gun of the invention having an openable pivoted shutter at the communicating passage.

There are provided within gun body 11 main magazine 12 and auxiliary magazines 13 with common open communicating passage 15 for balls to travel therethrough from magazine 13 to magazine 12 within the body. The partition wall dividing magazines 12 and 13 from each other is designated at 14, the trigger at 16, the striker at 17, the spring for advancing striker 17 at 18, the discharge bore for balls at 20, the feed hole for balls at 21 that communicates discharge bore 20 with magazine 12, the loading aperture at 22 for balls into both magazines 12 and 13, and the openable cover at 23 for loading aperture 22. Communicating passage 15 has openable pivoted shutter 24 which is stopped in rotation at stopper projection 25 prepared in the side of auxiliary magazine 13 in such fashion that shutter 24 clockwise rotates toward main magazine 12 but not toward auxiliary one 13 for stopper projection 25, allowing free passage for balls 19 from magazine 13 into magazine 12 but preventing once migrated balls 19 in magazine 12 from returning to their original magazine 13, thereby allotting a specified character to balls 19 in travelling course.

In accordance with the invention with such structural design as mentioned, when body 11 lies horizontally as illustrated, balls 19 lie stationarily stored in magazines 12 and 13, but when it is held in discharge position, and trigger 16 drawn, one of the balls 19, fed through feed hole 21 into discharge bore 20, discharged from this by means of striker 17 with the help of spring 18, vibrations, changes in angular inclination or the like thereby produced in body 11, automatically work to feed magazine 12 through communicating passage 15 with fresh supply from auxiliary magazine 13. As it is seen, the feeding is carried out automatically by vibrations or another angular inclination naturally produced in body 11 during discharge operation without conscious care of the user to feed. Therefore, the structural design assures such effect that, keeping pace with the consumption of balls 19 in main magazine 12 either directly communicating with or lying in the vicinity of feed hole 21, balls stored in auxiliary magazine 13 are fed automatically and without failure from magazine 13, and such repeated trouble is absolutely avoided as to pick up balls 19 from magazine 13, for example, with fingers, for feeding magazine 12 with fresh supply. The provision of a plurality of magazines like 12 and 13, so long as these are furnished with communicating passage 15, proves very effective in securing the largest possible capacity for the magazine equipment by best turning to account space within body 11 and introducing more magazines without impairing actions of other elements of mechanism.

Furthermore, with the invention, the provision of a plurality of magazines within the body as main 12 and auxiliary ones 13 of respectively distinct characteristic arranged on a definite plan for vast collections of balls in the possible largest capacity magazine equipment in such fashion that at least the one for a collection of many balls to be directly fed into discharge bore 20 and the other for that of those for replenishing the other in consumption, removes the possibility of disorderly collection of carelessly fed balls 19 being jammed up in feed hole 21 and enables the other collection to be fed into the hole in orderly suc-

cession. In addition, partition walls 14 dividing both magazines from each other and using a significant influence upon the establishment of undisturbed feed of balls into the discharge bore, permits free design in shape, size and angular inclination, regardless capacity of magazines 12 and 13, and placement in the best effective position with respect to feed hole 21 and magazine 12 to the securement of the most expedient and effective feed performance. In the form of embodiment of the invention illustrated where communicating passage 15 is furnished with shutter 24 and stopper projection 25, balls freely travel from auxiliary magazine 13 through openable shutter 24 to main magazine 12, but, once have travelled to magazine 12, are prevented from travelling back to magazine 13 for shutter 24 which does not open into magazine 13. This provides an advantage that balls are always controlled to take the prescribed course of travel from magazine 13 to magazine 12 and not vice versa. Practical results proved to be excellent beyond expectation. The necessary structural design in accordance with the invention is very simple, and it is obvious that it may be easily applied to nearly any toy guns. It displays splendid effects and removes such disadvantages in the prior art toy guns as the disturbed feed of balls to the discharge bore ascribable to the disorderly store of many balls without remedy, the disappointingly small capacity of magazine in contrast to apparent bulkiness of the body, and the like, and indeed realizes complete utilization of the internal space of the body for magazine equipment and control of the orderly travelling course for balls without particular care being taken by the user from without. There allows of course modification of design without departing from the scope of the invention.

I claim:

A toy gun capable of discharging balls comprising: 35
a main body;

two magazines within said body, consisting of a front main magazine and a rear auxiliary magazine; a partition separating said main magazine from said auxiliary magazine, said partition extending into a passage connecting said main magazine and said auxiliary magazine, and comprising a wall defining a feed opening through which said balls are permitted to drop to a position to be fired; means for striking each of the balls stored in said main magazine after it passes through the feed opening and is aligned with a discharge hole in the forward portion of the main body; a shutter pivotally suspended from said body and positioned in said passage between said main magazine and said auxiliary magazine, directly above said feed opening; and a stop in said passage adjacent to the rear surface of said shutter, preventing said shutter from moving rearward of said feed opening, whereby balls in said main magazine are prevented from returning to said auxiliary magazine once they have passed into the main magazine.
